DESIGN FOR A COMBINATION LIGHTER,
CIGARETTE RECEPTACLE, AND ASH
TRAY

Walter Baier, Wuerttenberg, Germany

Application December 10, 1948, Serial No. 150,078

Term of patent 14 years

(Cl. D85—2)

To all whom it may concern:

Be it known that I, Walter Baier, a citizen of the German Reich, residing at Wuerttenberg, United States Zone, Germany, have invented a new, original, and ornamental Design for a Combination Lighter, Cigarette Receptacle, and Ash Tray, of which the following is a specification, reference being had to the accompanying drawing, forming part thereof.

Fig. 1 is a perspective view of a combination lighter, cigarette receptacle, and ash tray, showing my new design, the lighter and receptacle in closed position.

Fig. 2 is a perspective view thereof, the lighter and receptacle being in open position.

I claim:

The ornamental design for a combination

lighter, cigarette receptacle, and ash tray, substantially as shown.

WALTER BAIER.
